UNITED STATES PATENT OFFICE.

ZENO C. HABERMAN, OF GARDEN CITY, SOUTH DAKOTA.

FABRIC-MEASURING MACHINE.

1,356,446.

Specification of Letters Patent.

Patented Oct. 19, 1920.

Application filed February 16, 1918. Serial No. 217,631.

To all whom it may concern:

Be it known that I, ZENO C. HABERMAN, citizen of the United States, residing at Garden City, in the county of Clark and 5 State of South Dakota, have invented new and useful Improvements in Fabric-Measuring Devices, of which the following is a specification.

This invention relates to measuring devices, and one object is to provide means especially adapted for measuring oilcloth as it is being unwound from the original roll and again wound into a roll for delivery to the customer.

15 A further object is to provide in a device of the type indicated a framework including means for supporting a winding rod or the like, this rod being slotted longitudinally for engaging the material to be measured, 20 means for receiving the roll from which the oilcloth is unwound, and measuring means supported by the framework and located between the roll receiving means and the rod or roller upon which the oilcloth is to be 25 wound prior to delivery.

A still further object is to provide a measuring device including a rotatable member mounted within a suitable casing and actuating means therefor including a rotatable member mounted between the roll of cloth, and the aforesaid slotted rod or roll.

With the foregoing and other objects in view, the invention consists in the novel construction, combination, and arrangement of elements hereinafter described and claimed.

In the drawings,

Figure 1 is a view of the device in end elevation.

40 Fig. 2 is a front elevation of the upper portion of the structure looking from the left in Fig. 1.

Fig. 3 is a detail view of an indicating device, parts being broken away.

45 Fig. 4 is an edge view of certain of the elements of the indicating device used in the construction shown in Fig. 1.

A framework 10 is provided with any suitable supporting devices such as 12, for 50 receiving a plurality of rolls of oilcloth or the like, and upon this frame are mounted a plurality of standards 13 and 14, these standards being slotted at their upper ends as shown at 15 and supporting a rod or roller 16, upon which the material to be

measured and delivered is wound. This roller 16 is slotted longitudinally as shown at 17 and is provided with a collar or collars 18 for retaining the material within the slotted portion at the time the winding operation is started. Rod 16 is operated by means of a crank 19. A longitudinal rod 20 connects the upper portions of standards 13 and 14.

An upwardly inclined plate 22 extends 65 longitudinally of the framework and connects the standards, being slotted longitudinally throughout its length as shown in 23, whereby any suitable cutting implement may be employed and guided during the 70 operation of severing the sheet of material after having been measured.

The roll of material to be measured is designated 24 and is carried within any suitable supporting means as shown at 25, 75 the material passing therefrom upwardly between roller 26 and the small pressure roller 27, and thence to the slotted roller 16.

In the drawings the element 25 is shown as being of trough-like formation, one side 80 of the trough presenting a surface positioned to guide the sheet of material being unrolled and measured directly to the inclined member. This permits rolls of different widths (and perhaps wound on wooden rolls of 85 different lengths), to be measured, without the adjustment of any supporting devices, such as bearings for the ends of the wooden rolls.

The shaft 28 carrying roller 26 is provided with a pinion 29 meshing with a gear wheel 30 mounted on a shaft 31. A pinion 32 on shaft 31 meshes with the gear wheel 33 carried rigidly with disk 34 upon a common spindle 34' the disk constituting an indicating device, and having graduations indicating yards and fractions of yards. The indicating device may be mounted in any suitable casing as shown at 35.

As shown in Fig. 1 the inclined member 100 is tangential with reference to the surface of the roll being unwound, due to the relative position of the inclined member and trough, and the material is unwound in the most natural and direct manner possible.

105 In Fig. 3 I have shown another form of indicating device comprising a ring member 38 provided with a series of graduations indicating yards and fractions of yards, and with a series of apertures 39 with which 110

the pinion 40 meshes, this pinion last named corresponding to pinion 32 on shaft 31 previously referred to.

What is claimed is:

- 5 In a device of the class described, a framework including a plurality of uprights, a winding device extending between said uprights and provided with a longitudinal slot clamping means on said device, an inclined member extending between the uprights and across which the material to be wound passes, said member being slotted longitudinally for guiding a cutting device, a trough-like member for supporting a roll 10 of material to be measured and having a surface merging into the surface of the in- 15

clined member, the latter being tangential with reference to the roll to be unwound, and the inclined member being tangential with reference to the surface of the rotary member contacting with the material, a rotary member adapted to bear against the material to be measured, a gear wheel carried thereby, a shaft, a gear wheel on said shaft meshing with the gear wheel first 25 named, an indicating device and a gear wheel carried thereby, and means carried by the shaft meshing with the gear wheel last named.

In testimony whereof I affix my signature. 30

ZENO C. HABERMAN.
